LUGGAGE COMPARTMENT COVER

James Donald, Marvin W. Stimson, and Raymond Birza, Denver, Colo., assignors to Shwayder Bros., Inc., Denver, Colo., a corporation of Colorado

Application January 7, 1949, Serial No. 69,684

8 Claims. (Cl. 190—51)

1

This invention relates to luggage compartment covers, and more particularly to covers for compartments of luggage such as traveling cases, wardrobe cases, suit cases, trunks and the like, being especially useful for wardrobe compartments which are adapted to contain suits, dresses and similar articles.

Prior covers for wardrobe compartments of luggage have been glued, tacked, stapled or similarly fastened to one edge of the compartment, and releasably attached to the opposite edge. Such covers are conventionally provided with one or more strips of elastic, sewed thereinto, so that the cover can be stretched over the clothing or like articles packed in the compartment, to assist in retaining the same in the compartment, and also to protect the same against soiling or contact with other articles, as during packing and unpacking. A popular type of luggage case is divided into two compartments, one of which is fitted as a wardrobe compartment. Such a case may be constructed so as to rest on a support such as a stand or table, with the wardrobe compartment extending upwardly, when the case is in open position. Access to the wardrobe compartment is obtained by unfastening the cover at the lower end, and the cover may then be placed rearwardly over the top of the case, with the free end of the cover falling down behind the upper or wardrobe compartment. The manner in which the edge of the cover is attached to one compartment wall, and the manner in which the opposite edge of the cover is removably attached to the opposite wall of the compartment, is of considerable importance. Due to its being fastened and unfastened many times, the cover is subject to the possibility of becoming worn, stretched out of shape, or an edge or portion thereof torn away from or dislodged from the compartment wall to which it is attached.

Among the objects of the present invention are to provide a novel compartment cover for luggage and the like; to provide such a cover which is particularly adapted to be utilized in connection with a wardrobe compartment; to provide such a cover, one edge of which is readily and simply attached to a wall of the compartment; to provide such a cover, the opposite edge of which is releasably attached to the opposite wall of the compartment; to provide such a cover which will withstand much wear and abuse, and which may be stretched and restretched laterally or longitudinally but does not tend to wrinkle unduly or to get out of shape; to provide such a cover which is not readily dislodged or torn

2

away from the luggage case; to provide such a cover which, after installation, is neat and attractive in appearance; to provide such a cover which is relatively economically manufactured; and to provide such a cover which may be made in a variety of different sizes and shapes.

Additional objects and the novel features of this invention will become apparent from the following description, taken in connection with the accompanying drawings, in which:

Fig. 1 is a perspective view of a ladies' wardrobe case, shown in open position, the wardrobe compartment of the case being provided with a cover constructed in accordance with this invention;

Fig. 2 is a condensed vertical section taken along line 2—2 of Fig. 1, showing the cover in closed position;

Fig. 3 is a vertical section of the upper portion of the wardrobe compartment, showing the cover thrown back over the top thereof;

Fig. 4 is an enlarged fragmentary transverse section, taken along line 4—4 of Fig. 1, at one edge of the cover;

Fig. 5 is an enlarged fragmentary section in horizontal instead of vertical position, taken along line 5—5 of Fig. 1, at the releasably attached edge of the cover;

Fig. 6 is an enlarged section similar to Fig. 5, illustrating a step in the manufacture of the cover;

Fig. 7 is an enlarged perspective end section, showing particularly the means for releasable attachment of the cover; and

Fig. 8 is an enlarged section in horizontal instead of vertical position, taken along line 8—8 of Fig. 1, at the attached edge of the cover.

As illustrated in Fig. 1, a cover C, constructed in accordance with this invention, may be provided for the wardrobe compartment W of a luggage case, having also a compartment L, which may be the lower compartment when the luggage case is in open position, as shown. For greater convenience in use, the case is preferably opened with the wardrobe compartment W uppermost, and the case may be provided with conventional stop levers or the like, to hold the wardrobe compartment W in a generally vertical position, while the compartments may be conventionally hinged together, and the crack therebetween which would ordinarily be exposed when the case is in open position, covered by a strip 10, normally made of the same material as the lining or liner 11. The liner 11 may be constructed in the manner disclosed and claimed in our co-

pending application Serial No. 68,948, filed January 3, 1949, and entitled "Luggage Compartment Liners," although a lining constructed in any other suitable manner may be utilized. The wardrobe compartment W, as in Figs. 1 and 2, may be provided with several hangers 12, a cord 13 and a frame 14 having a top bar 15, frame 14 being pivotally mounted on brackets 16, for more conveniently packing suits, dresses and the like. The case also provides walls defining the compartments, those pertinent to the present invention being the top wall 17 and the bottom wall 18 of the wardrobe compartment W, it being understood that the terms "top" and "bottom," as well as the "upper" and "lower" edges of the cover C, are only relative, and refer to the compartment W or cover C when in the position of Fig. 1.

Access to the wardrobe compartment W is obtained by detaching the cover C from hooks 19 of Fig. 2, and throwing the cover C back over the top of the case, as to the position of Fig. 3. In this position, suits, dresses and the like may be placed in or removed from the compartment, a convenient operation in packing being to hang all of the suits, dresses or the like on the hangers 12 with the frame 14 in downwardly pivoted position and the cord 13 unfastened. The cord 13 may then be fastened across the lower end of the compartment W, and any excess portions of the clothing folded back over the bar 15 at the end of the frame 14. The frame 14 may then be pushed back into the compartment, and the cover C fastened over the compartment.

The cover C may be made primarily of a cloth or fabric 20, of any suitable material, such as silk, rayon, plastic film or the like, which will present an attractive appearance, and in one or more layers, as desired. The cover C is, in general, longer than necessary to cover the compartment, fabric 20 being gathered and provided with a number of elastic strips 21, such as three, inserted in or sewed to the lining. When three elastic strips 21 are used, one may extend centrally, and the other two along the outer edges of the cover, as shown generally in Fig. 1. The center elastic strip 21 may be stitched directly to the underside of fabric 20, while each side elastic strip 21, as in Fig. 4, may be enclosed within fabric, such as within a strip 22, which may be stitched to the fabric 20 of the cover and also to elastic strip 21, as shown.

In accordance with the present invention, the cover C may be provided at its upper and lower edges with a novel edge assembly, comprising a doubled stiffener strip 24 or 24' of material preferably stiffer than the fabric 20, such as cardboard, and a bar 25 formed of metal, such as steel, aluminum, or other material stronger than fabric 20 or strip 24. Bar 25 may be a solid rod, having a circular cross section, as shown, or may be a tube or bar of any other cross sectional shape, such as elliptical, square, rectangular, or the like, any of which may also be hollow. At the lower or releasably attached edge of cover C, and as shown also in Fig. 5, the doubled cardboard strip 24 encloses bar 25 and is in turn enclosed by a covering strip 26, preferably formed of the same material as fabric 20 and attached to the cardboard strip 24 and fabric 20 by rows of stitching 27 and 28, respectively. The cardboard strip 24 is preferably longer than the rod 25, so that the ends of strip 24 and fabric strip 26 will extend past the end of rod 25 and the latter will not be visible, as evident from Fig. 1, unless viewed directly from the side or edge of the cover C. As

in Figs. 5 and 6, the ends of covering strip 26 are lapped to the inside of cardboard strip 24, and the fabric 20 is inserted within the cardboard strip 24. Stitching 27 may be disposed adjacent the edges of the cardboard strip 24, while stitching 28 may be disposed adjacent the edge of fabric 20, in a position spaced from the bend of the cardboard strip 24, so that a space 29 is formed which, as in Fig. 5, is adapted to receive the bar 25. As will be evident from Fig. 5, the cardboard strip 24 has legs of equal width extending along the fabric 20 and attached thereto by stitching 27 and 28. While these legs are preferably of equal length, it will be understood that the legs 15 may be of unequal width. The cardboard strip 24 is preferably sufficiently flexible so as to be capable readily of having the opposed sides forming the bar receiving space moved together and spread apart. Thus, the cardboard, cardboard covering strip 26, and fabric 20 may be assembled and stitched together while in flat position, as in Fig. 6, prior to the insertion of bar 25 into the space 29, or stitched after insertion of the bar 25, as in Fig. 5. This is of particular advantage, since all of the stitching operations may be performed with the cover flat, whether or not the metal bars or rods 25 are in place.

In further accordance with this invention, to provide a detachable connection at the desired edge of the cover C, an eyelet 30, as in Fig. 7, may be passed through and clinched to the edge assembly, closely adjacent each side thereof. As will be evident, each eyelet 30 preferably passes through both sides of cardboard 24, as well as through fabric cover strip 26 and fabric 20, between stitching 27 and 28. Each eyelet 30 may be disposed in line with or pass through one of the side elastic strips 21, and is adapted to engage a hook 18, which may be formed as an ear or extension of bracket 16, on which the frame 14 is also mounted, as in Fig. 2. It will be evident, of course, that the hooks 19 may be formed separately and attached to the bottom wall 18 of the compartment in a suitable manner, or mounted in any other convenient manner, as on one of the side walls of the compartment.

In further accordance with this invention, a similar edge assembly is provided at the upper or opposite edge of the cover C, as shown in Fig. 8, the position of the bar 25 being reversed with respect to the end of the fabric 20, which is attached, as by stitching 34, to the rear of the edge assembly, instead of inserted between the edges of strip 24'. The strip 24' is made of suitable material, such as cardboard, as before, and may be similar to the strip 24 of Figs. 5 and 6, or have a front leg 32 wider than the rear leg 33, as shown in Fig. 8. One edge of covering strip 26' therefore may be attached, as by an odorless synthetic adhesive, to the inside or rear of the front leg 32, and the strip 26' then passed around the strip 24' to be lapped over the rear leg 33, and attached thereto by stitching 34, which preferably extends through both layers of cardboard. A second row of stitching 28' extends through both layers of the cardboard and covering strip to define the space in which the bar 25 is inserted. The edge assembly of Fig. 8 may be attached to the top wall 17 of the compartment by screws 35, each of which extends through the liner 11 and into the wall 17. One of the screws 35 may be disposed beneath each of the side elastic strips 21, while a third screw may also be disposed beneath the central elastic strip, or two screws may

be disposed to either side thereof, if necessary to accommodate a bracket 36, of Fig. 1, on which the hangers 12 are supported. As will be evident, staples, pins, bolts, or other forms of attaching means may be substituted for screws 35.

As will be evident from the foregoing, the luggage compartment cover of this invention fulfills to a marked degree the requirements and objects hereinbefore set forth. One edge of the cover is easily attached to a wall of the compartment, such as merely by a series of screws. Also, the opposite edge of the cover is releasably attached to the opposite wall of the compartment, as through the eyelets 30 and hooks 19. The cover is particularly adapted to withstand wear and abuse, does not tend to get out of shape, and cannot readily be dislodged or torn away from the compartment, since each bar 25 is sufficiently strong to withstand the pull of the elastic strips, and also other stresses which may be placed on the cover. Each edge of the cover is also relatively inflexible, due to the strength imparted thereto by the bar or rod 25. The stiffener or cardboard strips 24 and 24', particularly when doubled over, provide sufficient strength to transfer any stresses imposed on the fabric 20 to the rods 25, and vice versa. The cover is neat and attractive in appearance, since at the lower edge, i. e. shown in Figs. 5 and 6, all raw fabric edges are enclosed within the stiffener strip 24, while at the opposite or upper edge, as shown in Fig. 8, there are no exposed edges, since the edge of the fabric 20 is behind the edge assembly, and the edges of the covering strip 26' are behind or between the strip 24'. Furthermore, the bars 25 are hidden, since each is enclosed by a stiffener strip 24 or 24'. The cover is relatively economically manufactured, since all stitching operations may be carried out with the parts in flat position, and the bars 25 are readily inserted either before or after stitching has been completed. The fabric 20 is conveniently gathered and the elastic strips 21 attached thereto, prior to attachment of the edge assemblies, although any desired procedure may be followed in manufacturing.

As will also be evident, the cover may be made in a variety of different sizes and shapes, to fit any desired compartment; the size and shape of the stiffener or cardboard strips, as well as other parts, may be varied; and materials other than those indicated may be used in making such strips, as well as any of the other parts. Thus, material other than steel or aluminum, such as brass, bronze, magnesium or alloys thereof, or others, may be used for the bars 25; the fabric 20 may be any suitable textile or other fabric, or may be a sheet of material, such as plastic, and may or may not be the same material as the lining, as desired, while the compartment also may be unlined; the stiffener strips 24 may be formed of cardboard, as indicated, or of other material, such as plastic, fabric or paper plasticized or otherwise treated to produce the desired relative stiffness; and the covering strips 26 and 26' may be made of the same or different material than the cover fabric 20. While the length of bars 25 is preferably slightly less than the width of the cover C, the length of the bars may be varied, and more than one bar may be inserted in the space 29.

While the cover of this invention has been shown as applied to a ladies' wardrobe case, it

will be evident that it may be applied to other types of luggage, such as different types of traveling cases, overnight cases, other wardrobe cases, suit cases, and even to trunks, particularly small trunks, and other types of luggage. The cover of this invention may also be used in non-traveling equipment, such as equipment which includes storage compartments for clothing and other articles, and also may be applied generally to any compartment for which a cover is to be provided.

While a specific embodiment of this invention has been described in detail, and certain changes therein described or indicated, it will further be evident that other embodiments may exist, and that various other changes may be made, all without departing from the spirit and scope of this invention.

What is claimed is:

1. In a cover for a luggage compartment or the like, said cover being formed principally of fabric or the like, a relatively rigid bar extending along one edge of said fabric; a folded strip of material stiffer than said fabric but sufficiently flexible so as to be capable readily of having the opposed sides thereof moved together and spread apart, said folded strip enclosing said bar and having legs of unequal width extending along said fabric; and means attaching said fabric to said folded strip and the edges of said folded strip together, at least a portion of said attaching means extending along said folded strip in spaced relation to the folded edge thereof and defining a space for receiving said bar.

2. In a cover for a luggage compartment or the like, the improvement defined in claim 1, including a covering strip for said folded strip, and enclosing the same, the edges of said covering strip extending around the edges of said folded strip, and wherein said fabric is attached to said covering strip and folded strip on the outside of the narrower leg of said folded strip.

3. In a cover for a luggage case or the like having walls defining a compartment, said cover being formed principally of fabric or the like which is gathered and has an elastic strip attached thereto at least adjacent each side edge, the improvement which comprises a relatively rigid bar extending along one edge of said fabric; a folded strip of material stiffer than said fabric and enclosing said bar, said folded strip having legs of equal width extending away from said bar; a covering strip of fabric enclosing said folded strip and having edges extending between the legs of said folded strip, stitching attaching said fabric to said folded strip and said covering strip, a portion of said stitching extending along said folded strip in spaced relation to the folded edge thereof and defining a space for receiving said bar, and another portion of said stitching being disposed adjacent the edges of said legs; an eyelet extending through said folded strip, covering strip and fabric and clinched thereon, adjacent each said side elastic strip; a hook for each eyelet mounted on a wall of said compartment to provide a releasable attachment for said cover; and means for attaching the opposite edge of said cover to the corresponding wall of said compartment.

4. In a cover for a luggage case or the like having walls defining a compartment, said cover being formed principally of fabric or the like, the improvement which comprises a relatively rigid bar extending along one edge of said fabric;

a folded strip of material stiffer than said fabric and enclosing said bar and having legs of unequal width extending away from said bar; a covering strip of fabric enclosing said folded strip; one edge of said covering strip being adhesively attached to the inner edge of said wider leg and the opposite edge of said covering strip extending around the edge of said narrower leg and between said legs; stitching attaching said fabric to said strips, a portion of said stitching extending along said folded strip in spaced relation to the folded end thereof to define a space for receiving said bar, and another portion of said stitching extending along said folded strip adjacent the edge of said narrower leg, at least one of said portions also attaching the edge of said fabric to the outside of said narrower leg; a series of screws extending through said folded strip and covering strip and into a wall of said compartment, to attach said cover thereto with the edge of said fabric behind said bar and strips; and means for releasably attaching the opposite edge of said fabric to a corresponding wall of said compartment.

5. In a cover for a luggage case or the like having walls defining a compartment, said cover being formed principally of fabric or the like which is gathered and has an elastic strip attached thereto at least adjacent each side edge, the improvement which comprises a relatively rigid bar extending along one edge of said fabric; a folded strip of material stiffer than said fabric and enclosing said bar, said folded strip having legs of equal width extending away from said bar; a covering strip of fabric enclosing said folded strip and having edges extending between the legs of said folded strip; stitching attaching said fabric to said folded strip and said covering strip, a portion of said stitching extending along said folded strip in spaced relation to the folded edge thereof and defining a space for receiving said bar, and another portion of said stitching being disposed adjacent the edges of said legs; an eyelet extending through said folded strip, covering strip and fabric and clinched thereon, adjacent each said side elastic strip; a hook for each eyelet mounted on a wall of said compartment to provide a releasable attachment for said cover; a second relatively rigid bar extending along an opposite edge of said fabric; a second folded strip of material stiffer than said fabric and enclosing said bar and having legs of unequal width extending away from said bar; a covering strip of fabric enclosing said second folded strip, one edge of said covering strip

being adhesively attached to the inner edge of said wider leg and the opposite edge of said narrower leg; a covering strip extending around the edge of said narrower leg and between said legs; stitching attaching said fabric to said strips, a portion of said stitching extending along said wider leg and the opposite edge of said narrower leg, at least one of said portions also attaching the edge of said fabric to the outside of said narrower leg; and a series of screws extending through said folded strip and covering strip and into a wall of said compartment, to attach said cover thereto with the edge of said fabric behind said bar and strips.

6. In a cover for a luggage compartment or the like, said cover being formed principally of fabric, the improvement which comprises a rigid metal rod extending along one edge of said cover fabric; a folded strip of cardboard enclosing said rod and having legs extending along said fabric; a covering strip of fabric extending around said cardboard strip on the outside thereof; and stitching extending substantially parallel to said rod along a line spaced from the folded edge of said cardboard strip and passing through said cover fabric, said cardboard and said covering fabric strip, said stitching defining a rod receiving space.

7. In a cover for a luggage compartment or the like, as defined in claim 6, wherein said legs of said cardboard strip are of equal length.

8. In a cover for a luggage compartment or the like, as defined in claim 6, wherein said legs of said cardboard strip are of unequal length.
